DESIGN FOR WALLPAPER OR THE LIKE

Frank E. Leitch, Stamford, Conn., assignor to Stamford Wall Paper Company, Incorporated,
Stamford, Conn., a corporation of Delaware

Application January 4, 1940, Serial No. 89,288

Term of patent 3½ years

To all whom it may concern:

Be it known that I, Frank E. Leitch, a citizen of the United States, residing at Stamford, in the county of Fairfield and State of Connecticut, have invented a new, original, and ornamental Design for Wallpaper or the like, of which the following is a specification, reference being had to the accompanying drawing, forming part thereof.

The drawing is a plan view of a wallpaper showing my new design.

I claim:

The ornamental design for wallpaper or the like, as shown.

FRANK E. LEITCH.
